CARL WALTHER FERNHOLTZ, OF LOS ANGELES, CALIFORNIA, ASSIGNOR TO FERNHOLTZ MACHINERY COMPANY, OF LOS ANGELES, CALIFORNIA, A CORPORATION OF CALIFORNIA.

APPARATUS FOR FORMING BRIQUETTES.

Application filed January 11, 1926. Serial No. 30,476.

This invention pertains more particularly to a method of forming briquettes from a pulverulent material and it consists in expelling substantially all the air therefrom after its introduction to the compression chamber and also from the chamber before finally compressing the material into briquette form, whereby to greatly increase the density and hardness of the finished product.

Another object of the invention is the provision of an apparatus especially adapted for use in connection with the method above set forth in which the molding chamber is provided with air venting ducts in its non-compressing portion of the chamber for the exit of the air that is expelled from the material and chamber during the operation of the apparatus.

A further object is to provide a simple mechanism for automatically preventing the clogging of the mold air venting ducts with the briquetting material during the operation of the apparatus.

In briquette forming operations where lignite, coal or coke dust, and other compressible materials are employed, the inlet end of the mold chamber through which the compressing material passes during the die forming operation entrains therein a certain percentage of air as well as the material, and also an excess of molding material, which if not expelled from the die chamber prior to a compressing operation oftentimes seriously affects the molded product.

By means of the present method of briquetting substantially all the air in the material to be compressed is automatically expelled therefrom together with any air or excess material in the compressing chamber on an operation of the apparatus, the air vents leading from the molding or die chamber being continuously freed of material to prevent clogging.

The above objects are accomplished by means of the apparatus described in the following specification, reference being had to the drawings annexed hereto, in which:

Fig. 1 is a side elevation of a portion of a briquetting apparatus showing the die mold chambers and the air venting means connected thereto.

Figure 2 is a plan view of the same partly in section to show the disposition of the air venting ducts.

Fig. 3 is a transverse section taken on line 3-3 of Fig. 2, looking in the direction of the arrows thereon.

Fig. 4 is an enlarged sectional detail of one side of the apparatus showing one of the vent ducts, and the material conveying means mounted therein.

As the present invention relates specifically to a method for relieving the mold cavity of a briquetting apparatus and also the molding material of any air that may be entrained therein during a compressing operation, and also to expel any excess molding material not required, I have illustrated only such portions of an apparatus of usual form that directly appertains to my invention.

The apparatus herewith illustrated consists of a frame 5, provided with an elongated horizontally disposed molding cavity or chamber 6 open at either end, a vertically disposed material feeding chute 7 leading from the upper end of the frame and terminating at the rear end of the molding cavity, a material feed hopper 8, bolted to the frame communicating with the upper end of the material feeding chute 7, supplying and controlling the feed of material to the chute. The die plunger 9 is horizontally disposed in line with the molding cavity and is reciprocated back and forth in a mold forming operation by the usual reciprocating mechanism, not shown.

In order to expel any air from the molding cavity that may be entrained with the material being compressed on an operation of the plunger, and also to relieve the cavity of any excess molding material, two transversely disposed air vent bores 10, 11, are formed in the side walls of the frame, said bores preferably being of cylindrical form and lead from the rear end of the molding cavity outwardly and forwardly through the side walls of the apparatus. As the bores 10, 11, are located at the extreme rear end of the molding cavity where the briquetting material is delivered thereto, it will be apparent that any air that may be entrained with the molding material on an operation of the plunger will be quickly expelled through the bores, thereby greatly improving the quality of the finished product and at the same time increasing its hardness and density.

As the air passing through the vent bores will carry a certain amount of the briquetting

material therewith, means are provided for continuously cleansing or freeing the bores of the material, and in the accomplishment of this end, a small conveyor 13 of screw form 5 is mounted in each duct, the outer end of the shaft of each conveyor being connected by a universal coupling 14 with a transversely disposed operating shaft 15 mounted in a bearing 16 secured by means of an arm 17 to the 10 side wall of the frame, as clearly shown in Fig. 4 of the drawing. Each of shafts 15 beyond the bearing 16 has secured thereto a pulley 18, said pulleys being belted to other pulleys 19 carried by the ends of a transversely 15 disposed shaft 20 mounted in bearings 21 secured to the top wall of the frame of the apparatus. Shaft 20 is provided with a pulley 22 belted to a suitable source of power, not shown.

20 In order that the briquetting material delivered from the air vent bores may be conveyed away from the apparatus, downwardly extending chutes 23, disposed directly below each vent bore, are provided, the falling ma-

terial being conveyed away to a suitable place 25 of deposit by means of a conveyor mechanism 24 of any suitable type.

It will thus be seen that by providing air vent bores leading from the compressing mold cavity of briquetting machines, the 30 quality of the products is increased materially with respect to its density and hardness.

What I claim is:

1. In a briquetting apparatus a frame 35 provided with a mold cavity having an air vent, and means mounted within said vent for maintaining the same free of molding material during the operation of the apparatus.

2. In a briquetting apparatus a frame provided with a mold cavity having an air vent 40 leading from said cavity adjacent its open material feeding end, and means mounted in said vent for conveying material therefrom during the operation of the apparatus.

In witness that I claim the foregoing I have 45 hereunto subscribed my name this 30th day of November, 1925.

CARL WALTHER FERNHOLTZ.
